(57) **CLAIM**

The ornamental design for a VCR and DVD player combination, as shown and described.

DESCRIPTION

FIG. 1 is a front elevated view of a VCR and DVD player combination showing my new design.

FIG. 2 is a rear elevated view of the VCR and DVD player combination.

FIG. 3 is a right side elevated view of the VCR and DVD player combination.

FIG. 4 is a left side elevated view of the VCR and DVD player combination.

FIG. 5 is a top plan view of the VCR and DVD player combination; and,

FIG. 6 is a bottom plan view of the VCR and DVD player combination.

The broken line showing on FIG. 1 is for illustrative purposes only and forms no part of the claimed design.
